ABSTRACT

A magnetic deflection apparatus for displacing an electron beam in a cathode ray tube, and more particularly a deflection yoke for use in a color television receiver which comprises a plurality of deflection coil units arranged contiguously in the axial direction of the tube, whereby the deflection field at the central portion of the deflection coil units or the deflection field on the electron gun side of the central portion has a barrel field distribution and the deflection field on the screen side has a pincushion field distribution, thereby easily correcting pincushion and convergence distortions.

DEFLECTION COILS PRODUCING PINCUSHION AND BARREL DEFLECTION FIELDS

The present invention relates to a magnetic deflection apparatus used in a color television receiver to displace an electron beam therein.

The characteristics of a deflection yoke employed in a color television receiver has various effects on the picture quality of a color picture tube. While some of these effects may be corrected by means of circuit designing, there are some others which may not be readily corrected by circuit designing and which are thus entirely dependent on the characteristics of a deflection yoke used. For instance, while pincushion distortion may be corrected by means of a specially designed circuit, it is difficult to correct convergence distortion by means of circuit designing. As a result, since the above-mentioned convergence distortion and other cannot be corrected by means of circuit designing, it has been customary to discard the deflection yoke as a reject, if the variation in the characteristic of a deflection yoke caused during the manufacturing process exceeds the allowable limits.

It is therefore an object of the present invention to permit the correction of convergence distortion by circuitry means with a simple procedure.

It is another object of the present invention to permit the correction of pincushion distortion with more ease than has been the case in the past.

It is a further object of the present invention to permit the correction of convergence distortion along with the correction of pincushion distortion.

It is a still further object of the present invention to eliminate the heretofore employed pincushion correction circuit, thereby simplifying the circuit construction and reducing the cost of a television set.

The above and other objects, features and advantages of the present invention will become more apparent from considering the following detailed description taken in conjunction with the accompanying drawings, in which:

FIG. 1 is a diagram showing a magnetic field distribution of a prior art deflection yoke;

FIG. 2 is a side view showing, part in section, of an embodiment of a deflection yoke according to the present invention;

FIG. 3 is a section taken on the line III—III of FIG. 2;

FIG. 4 shows a magnetic field distribution of the deflection yoke shown in FIG. 2;

FIG. 5 is a side view of another embodiment comprising three of the contiguously arranged deflection coil units shown in FIG. 3;

FIG. 6 shows a magnetic field distribution of the deflection yoke shown in FIG. 5;

FIG. 7 is a side view showing, part in section, another embodiment of this invention comprising a plurality of contiguously arranged deflection coil units;

FIGS. 8a, 8b and 8c show the magnetic field distributions on the cross section of the respective deflection coil units of FIG. 7;

FIG. 9 is a section showing the wiring distribution of the deflection coil unit of FIG. 7 taken along the plane perpendicular to the tube axis;

FIG. 10 shows a magnetic field distribution of the deflection yoke shown in FIG. 11;

FIG. 11 is a side view showing, part in section, a deflection yoke having the field distribution characteristic shown in FIG. 10 and constituting one form of the practical application of the deflection yoke shown in FIG. 7;

FIG. 12 is a side view showing, part in section, another embodiment of the deflection yoke of the invention, wherein the distance between two deflection coil units is adjustable;

FIG. 13 is a side view of another embodiment of the deflection yoke of the invention, wherein the distance between the opposing end faces along the tube axis differs between the electron gun side and the screen side;

FIG. 14 is a section taken along the line XIV—XIV of FIG. 13;

FIG. 15 is a section taken along the line XV—XV of FIG. 13;

FIG. 16 is a side view of another embodiment of the deflection yoke of the invention, wherein that portion called a window having no coil windings therein differs in space between the electron gun side and the screen side;

FIG. 17 is a section taken along the line XVII—XVII of FIG. 16;

FIG. 18 is a section taken along the line XVIII—X-VIII of FIG. 16; and

FIG. 19 is a fractional explanatory view of another embodiment of the deflection yoke of the invention, wherein there is a difference in coil pitch angle between the electron gun side and the screen side.

Referring now to FIG. 1 of the drawing, there is shown a magnetic field distribution of a conventional deflection yoke. In the figure, the abscissa represents the distance in axial direction and the ordinate represents the magnitude of the magnetic field. The curve *a* indicates the magnetic field distribution in the axial direction of the deflection yoke and the curve *b* indicates the magnetic field distribution along the section perpendicular to the axis of the deflection yoke. The portions of the curves *a* and *b* above the horizontal line indicate the pincushion field regions, while those portions below the horizontal line indicate the barrel field regions. The strength of each of these regions is indicated by its distance from the horizontal line. The pincushion field region of the deflection yoke produces a barrel distortion in the picture, while the barrel field region produces a pincushion distortion in the picture.

It is well known that the deflection field must be uniform to satisfy the convergence characteristic and such a uniform field may be accomplished by distributing the windings in what is known as a cosine distribution. However, the magnetic field at the ends of a coil of finite length tends to take the form of a barrel field due to the breaking out of the magnetic field and therefore this situation must be compensated for by making the magnetic field inside the coil to take the form of a pincushion field to some extent. Accordingly, the magnetic field distribution of a conventional deflection yoke takes the form as shown in FIG. 1. The pincushion field regions provided by the portions of the curve *b* above the horizontal line in FIG. 1 distort the shape of a circular beam spot into an oval form. On the other hand, the barrel field region provided by the portion of the curve *b* below the horizontal line also distorts the beam spot from its circular shape into an oval form. In

this case, however, the magnetic fields of the respective regions act in the opposite directions. Therefore, if the area of the portion of the curve *b* above the horizontal line is equal to that of the other portion of the curve *b* below the horizontal line, no beam spot distortion will take place and hence there will be no occurrence of convergence distortion.

Also, with respect to the pincushion distortion characteristic, even the uniform magnetic field produces a rather pincushion-shaped picture. With these points in mind, it is evident from consideration of FIG. 1 that as mentioned earlier, in the vicinity of the peak of the magnetic field distribution in the axial direction of the deflection yoke (curve *a*), the magnetic field distribution on the section taken at right angles to the yoke axis forms a pincushion field, while, at the skirts of the axial magnetic field distribution (curve *a*), the magnetic field distribution on the section taken at right angles to the yoke axis (curve *b*) forms a barrel field. Consequently, a pincushion distortion is caused in the picture due to the effect of the barrel field region at the skirt on the screen side of the axial magnetic field distribution.

The present invention stems from the recognition of this fact that a pincushion distortion is produced in the picture by the screen-side barrel field region of the deflection yoke. Thus, according to the present invention, the screen-side deflection field of a deflection yoke is distributed in a pincushion field distribution to correct pincushion distortion of the picture and at the same time the deflection field at the central portion of the deflection yoke or on the electron gun side of the central portion is distributed in a barrel field distribution in correspondence with the pincushion field distribution on the screen side, thereby easily accomplishing the correction of convergence distortion along with the above-mentioned correction of pincushion distortion.

Referring now to FIG. 2 of the drawings illustrating an embodiment of the present invention, numerals 1 and 2 designate deflection yokes each having horizontal and vertical deflection coils. The deflection yokes 1 and 2 are arranged side by side in the axial direction of a cathode ray tube and are put together by a C-shaped spring 3. The spring 3 is provided with square projections 4. The square projections 4 are fitted in slits 6 formed in a housing 5 holding the deflection yokes 1 and 2 in place. The housing 5 is clamped on the neck portion of the cathode ray tube by a band 7.

In FIG. 3, numeral 8 designates a ring core of ferromagnetic material constituting a part of the deflection yoke 2, 9 main deflection coils, 10 auxiliary deflection coils. For purposes of clarification, the coils shown in the figure have a fewer number of turns than the actual number of turns and the coils on the outside of the core 8 are not shown since they are not necessary for the purposes of this discussion. The main deflection coil 9 is uniformly wound on the core 8, while the auxiliary deflection coil is wound respectively to overlap the main deflection coil 9 at the central portion and the outer sides thereof.

Here, the auxiliary deflection coil 10 at the central portion of the main deflection coil 9 is designated as 10a and the auxiliary deflection coil 10 at the outer sides of the main deflection coil 9 is designated as 10b.

With the arrangement described above, let it be assumed that the direction of current flow in the auxiliary

deflection coil 10a is opposite to that in the outer side auxiliary deflection coil 10b and that the direction of current flow in the auxiliary deflection coil 10b is the same as in the main deflection coil 9. Accordingly, at the central portion of the main deflection coil 9, the main deflection coil 9 and the auxiliary deflection coil 10a produce magnetic fields in such directions which cancel each other, while, at the outer sides of the main deflection coil 9, magnetic fields are produced in such directions that they are added together. As a result, the deflection field of the deflection yoke 2 is distributed in a barrel field distribution. On the contrary, if it is so arranged that the direction of current flow in the auxiliary deflection coil 10a at the central portion of the main deflection coil 9 is the same as the main deflection coil 9, then, at the central portion of the main deflection coil 9, the main deflection coil 9 and the auxiliary deflection coil 10a produce magnetic fields in such directions that they are added together, while, at the outer sides of the main deflection coil 9, magnetic fields are produced in such directions which cancel each other. Consequently, the deflection field of the deflection yoke 2 is distributed in a pincushion field distribution. This also applies to the other deflection yoke 1. Since the direction of current flow in the auxiliary deflection coil portions 10a and 10b is opposite to each other, the intensity of the axial magnetic field is constant. In other words, the magnetic field distribution on the transverse section can be changed without changing the form of the magnetic field distribution in the axial direction of the tube. This in turn means that the deflection characteristic can be changed without changing the deflection amplitude.

In FIG. 2, for example, if the direction of current flow in each of the auxiliary deflection coils in the deflection yoke 1 is selected so that the magnetic field distribution of this rear (electron gun side) deflection yoke 1 produces a barrel magnetic field and if the direction of current flow in each of the auxiliary deflection coils of the front (screen side) deflection yoke 2 is selected so that the magnetic field distribution of the deflection yoke 2 provides a pincushion magnetic field, a magnetic field distribution as shown in FIG. 4 results.

In FIG. 4, the curve *a*₁ indicates an axial magnetic field distribution and the curve *b*₁ indicates a magnetic field distribution on the section perpendicular to the tube axis. The occurrence of pincushion distortion is proportional to the distance between the curve *b*₁ and the abscissa. Since a difference in area between the pincushion region and the barrel region is responsible for the production of convergence distortion, the pincushion and convergence distortions can be corrected as desired by adjusting the ratio and intensity of current flow in each of the respective auxiliary deflection coils of the deflection yokes 1 and 2.

As above described, according to this embodiment, the correction of both pincushion and convergence distortions can be accomplished by means of two deflection coil units which are arranged side by side in the axial direction of the tube and are provided respectively with main and auxiliary deflection coils and in which the ratio and intensity of current flow in each of the auxiliary deflection coils of the respective deflection coil units are changed as desired. In this way, the pincushion correction circuit which has heretofore been necessary can be eliminated. This simplifies the

circuit construction and thus permits a reduction in the manufacturing cost.

FIG. 5 shows another embodiment of the present invention. The embodiment of FIG. 5 comprises three deflection yokes each having the same main and auxiliary deflection coils 9 and 10 as in the first embodiment and arranged side by side in the axial direction of a cathode ray tube. The direction of current flow in each of the auxiliary deflection coils is selected so that the magnetic field of a central deflection yoke 11 is distributed in a barrel field distribution. The direction of current flow in each of the auxiliary deflection coils of deflection yokes 12 and 13 arranged on either side of the central deflection yoke 11 is so chosen that the magnetic fields of the deflection yokes 12 and 13 are distributed in a pincushion field distribution. FIG. 6 shows the magnetic field distribution curves for this embodiment constructed as above described. In other words, in the vicinity of the peak of the axial magnetic field distribution, i.e., the curve a_2 , the magnetic field distribution on the section taken at right angles to the tube axis, i.e., the curve b_2 , takes the form of a barrel magnetic field and the transsectional magnetic field distributions (curve b_2) at the skirts of the axial magnetic field distribution (curve a_2) take the form of a pincushion magnetic field. Thus, by adjusting the intensity and ratio of current flow in each of the auxiliary deflection coils of the respective deflection yokes so as to make the area of both the barrel and pincushion regions equal to each other, a deflection yoke which is free from both pincushion and convergence distortions can be provided.

FIG. 7 is still another embodiment of the present invention. The embodiment of FIG. 7 comprises a plurality of deflection yoke subassemblies contiguously arranged in the axial direction of a cathode ray tube. The construction of this embodiment is such that the central deflection yoke subassembly has a barrel magnetic field distribution and the deflection yoke subassembly on each side of the central subassembly has a pincushion magnetic field distribution. The embodiment will now be explained in greater detail with reference to FIG. 7.

In the figure, numeral 20 designates a deflection yoke comprising a ferromagnetic core 21, three sets of horizontal deflection coils 23, 24 and 25 for horizontally deflecting an electron beam in a cathode ray tube 22 and three sets of vertical deflection coils 26, 27 and 28 for vertically deflecting the electron beam. The horizontal deflection coils 23, 24 and 25 and the vertical deflections coils 26, 27 and 28 are arranged contiguously in the axial direction of the tube.

FIGS. 8a, 8b and 8c show respectively the magnetic field distributions on the sections taken at right angles to the tube axis along the lines VIIIa—VIIIa, VIIIb—VIIIb and VIIIc—VIIIc of the horizontal and vertical deflection coils 23 and 26, the horizontal and vertical deflection coils 24 and 27, and the horizontal and vertical deflection coils 25 and 28, respectively. FIGS. 8a and 8c show respectively a pincushion field distribution and FIG. 8b shows a barrel field distribution.

Next, a method of producing pincushion and barrel magnetic fields will be explained. Referring now to FIG. 9, there is shown a winding distribution when the deflection coils are cut through in a plane perpendicular to the tube axis. With the winding distribution shown in FIG. 9, let it be assumed that n represents a

winding density at a given angle β . Then, if $n = n_0 \cos \beta$ and $m > 1$, the deflection coil exhibits a pincushion field distribution, whereas if $m < 1$, the deflection coil exhibits a barrel field distribution. In the above equation, n_0 represents a winding density when the angle β is zero. Therefore, it follows that in the deflection yoke 20 of FIG. 7, the deflection coils 23, 26 and 25, 28 have been wound with the winding distributions providing $m > 1$, while the deflection coils 24, 27 have been wound with the winding distribution providing $m < 1$. The value of m for the respective coils must be selected in such a manner that the occurrence of both pincushion and convergence distortions may be prevented. Thus, if the magnetic field produced by the central coil unit 15 is distributed in a barrel field distribution and the magnetic field produced by the coil unit on each side of the central coil unit is distributed in a pincushion field distribution and if the intensity of the respective magnetic fields is adjusted by a suitable winding distribution, 20 then there results a deflection yoke which is free from both pincushion and convergence distortions.

While the embodiment of FIG. 7 has been shown as applied to a saddle type deflection yoke, the present invention is not limited to it and the present invention 25 can be equally applied, for example, to saddle-toroidal deflection coils and toroidal-toroidal deflection coils with equal effectiveness.

On the other hand, an increase in the deflection angle for a deflection yoke has the effect of moving the peak 30 of an axial magnetic field distribution to the rear (to the electron gun side) as shown by the curve a_3 in FIG. 10. In this case, the transsectional magnetic field distribution may take a form as shown by the curve b_3 in FIG. 10. To accomplish such a magnetic field distribution, 35 a deflection yoke may be composed of two deflection coil units. In this arrangement, the respective deflection coils may be wound in accordance with the manner of the embodiment shown in FIG. 7 so that the deflection field of the rear (electron gun side) deflection coil unit consists of a barrel magnetic field and the deflection field of the front (screen side) deflection coil unit consists of a pincushion magnetic field. One form of this kind of arrangement is shown in FIG. 11.

In the embodiment of FIG. 11, numeral 30 designates a ferromagnetic core, 31 horizontal deflection coils wound on the electron gun side with a barrel magnetic field distribution, 32 horizontal deflection coils wound on the screen side with a pincushion magnetic field distribution, 33 vertical deflection coils wound on the electron gun side with a barrel magnetic field distribution, 34 vertical deflection coils wound on the screen side with a pincushion magnetic field distribution.

The horizontal and vertical deflection coils 31 and 33 on the electron gun side and the horizontal and vertical deflection coils 32 and 34 on the screen side are arranged side by side in the axial direction of the tube.

Further, a deflection yoke with a magnetic field distribution substantially as shown in FIG. 6 may be provided, if two deflection yokes each thereof having separately a magnetic field distribution as shown in FIG. 1 are arranged apart from each other.

One form of this arrangement is shown in FIG. 12. In the embodiment of FIG. 12, numeral 40 designates a deflection yoke subassembly disposed at the rear, i.e., on the electron gun side, and numeral 41 designates a deflection yoke assembly disposed at the front, i.e., on the screen side at a distance from the deflection yoke

assembly 40. The deflection yoke is composed of the deflection yoke subassemblies 40 and 41. The rear deflection yoke subassembly 40 consists of a ferromagnetic core 42 and horizontal and vertical deflection coils 43 and 44 having a pincushion field distribution. The front deflection yoke subassembly 41 consists of a ferromagnetic core 45 and horizontal and vertical deflection coils 46 and 47 having a pincushion field distribution. The deflection yoke subassemblies 40 and 41 are joined together by a metal joint 48. One end of the metal joint 48 is secured to the deflection yoke subassembly 41 and an elongated axial slit 49 is provided at the other end adjoining the deflection yoke subassembly 40 so that the deflection yoke subassembly 40 slides in the slit 49 to adjust the distance between the deflection yoke subassemblies 40 and 41. By adjusting the distance between the deflection yoke subassemblies 40 and 41, the area of the curve b_2 below the abscissa line, i.e., the barrel field distribution can be adjusted as desired. In other words, the correction of convergence distortion can be effected through the adjustment of distance between the two deflection yoke subassemblies. Of course, the correction of pincushion distortion is also possible.

FIG. 13 illustrates still another embodiment of the present invention. In the figure, numeral 50 designates a deflection yoke comprising a pair of deflection coil units 51 and 52 each having horizontal and vertical deflection coils. A distance D between opposed end faces 53 and 54 of the deflection coil units 51 and 52 along the tube axis (the line a—a') is made so that if the distance D at the rear (electron gun side) is designated as D_1 and D_2 represents the distance D at the front (screen side), then there is a relation

$$D_1 > D_2.$$

In other words, the distance D gradually decreases from the rear (electron gun side) toward the front (screen side). With this construction, it is possible for the deflection yoke 50 to produce a barrel field distribution at its rear portion and a pincushion field distribution at its front portion.

FIGS. 14 and 15 show respectively the sections taken along the lines XIV—XIV and XV—XV of the deflection yoke 50 shown in FIG. 13. In FIGS. 14 and 15, α indicates the angle of what is known as a window where there is no winding.

FIGS. 16 through 18 illustrate still another embodiment of the present invention. FIG. 17 is a section taken along the line XVII—XVII of the deflection yoke shown in FIG. 16, and FIG. 18 is a section taken along the line XVIII—XVIII of the deflection yoke shown in FIG. 16. As will be seen from these figures, a distance D between opposed end faces 62 and 63 of a pair of deflection coil units 60 and 61 along the tube axis is uniform. The construction of this embodiment is such that if α represents the angle of the central portion of the deflection coil units 60 and 61, i.e., the portion known as a window with no winding disposed therein, α_1 represents the angle at the rear portion (electron gun side) of the coil units and α_2 represents the angle of the front portion (screen side), then there is a relation

$$\alpha_1 < \alpha_2.$$

In other words, the angle α increases gradually from the rear portion toward the front portion.

With this construction, the same magnetic field distribution as the deflection yoke 50 shown in FIG. 13 can be provided for the deflection yoke 64, that is, a barrel field distribution at the rear portion and a pincushion field distribution at the front portion of the deflection yoke 64 can be obtained. The same results can be obtained by the combination of the methods of FIGS. 13 and 16.

FIG. 19 illustrates still another embodiment of the present invention. FIG. 19 shows a principal part of a toroidal deflection yoke. In the figure, numeral 70 designates a ferromagnetic core, 71 a coil wound on the ferromagnetic core 70. In this embodiment, the coil 71 is wound so that if β represents the angle of a single pitch of the coil 71, β_1 represents the angle β at the rear portion of the coil and β_2 represents the angle β at the front portion (screen side), then there results a relation $\beta_1 > \beta_2$. With this arrangement, similarly with the embodiment of FIG. 13, a barrel field distribution at the rear portion and a pincushion field distribution at the front portion can be obtained. In other words, the simultaneous correction of pincushion and convergence distortions can be effected.

It will thus be seen from the foregoing description that the deflection yoke arrangements of very simple construction according to the present invention can be used to effect the simultaneous correction of pincushion and convergence distortions. It will also be seen that the present invention eliminates the heretofore used pincushion correction circuit with resultant simplification of the circuit construction and a reduction in the manufacturing cost of television sets.

What we claim is:

1. A deflection yoke comprising a plurality of deflection coils arranged contiguously along a tube axis, and wherein the deflection field of said deflection coil located in the center of said plurality of deflection coils is distributed in a barrel magnetic field distribution, and the deflection field of said deflection coil located on each side of said centrally located deflection coil is distributed in a pincushion magnetic field distribution.

2. A deflection yoke comprising a plurality of deflection coils arranged contiguously along a tube axis, and wherein the deflection field of said deflection coil located on an electron gun side is distributed in a barrel magnetic field distribution, and the deflection field of said deflection coil located on a screen side is distributed in a pincushion magnetic field distribution.

3. A deflection yoke comprising a plurality of deflection coil units arranged contiguously in the direction of a tube axis, wherein each of said plurality of deflection coil units comprises horizontal and vertical deflection coils each thereof including a main coil wound in a uniformly distributed winding and an auxiliary coil overlapping said main coil to adjust a magnetic field distribution on a section taken at right angles to said tube axis, and wherein said auxiliary coil is wound so that the direction of current flow in said auxiliary coil overlapping the central winding of said main coil is opposite to that in said auxiliary coil overlapping the outer side winding portions of said main coil.

4. A deflection yoke according to claim 3, wherein the direction of current flow in each of said auxiliary coils of said deflection coil unit located on an electron gun side is selected so that said deflection coil unit located on the electron gun side has its deflection field distributed in a barrel magnetic field distribution, and

wherein the direction of current flow in each of said auxiliary coils of said deflection coil unit located on a screen side is selected so that said deflection coil unit located on the screen side has its deflection field distributed in a pincushion magnetic field distribution.

5. A deflection yoke according to claim 3, wherein the direction of current flow in each of said auxiliary coils of said deflection coil unit located in the center of said plurality of deflection coil units is selected so that said centrally located deflection coil unit has its deflection field distributed in a barrel magnetic field distribution, and wherein the direction of current flow in each of said auxiliary coils of said deflection coil unit located on each side of said centrally located deflection coil unit is selected so that said deflection coil unit on each side of said centrally located deflection coil unit has its deflection field distributed in a pincushion magnetic field distribution.

6. A deflection yoke according to claim 4, wherein the direction of current flow in the auxiliary coil portions wound on the outer side winding portions of the main coils in the deflection coil unit located on the electron gun side is the same with that in said main coils.

7. A deflection yoke according to claim 4, wherein the direction of current flow in the auxiliary coil portions wound on the central winding portions of the main coils in the deflection coil unit located on the screen side is the same with that in said main coils.

8. A deflection yoke according to claim 5, wherein the direction of current flow in the auxiliary coil portions wound on the outer side coil portions of the main coils in the centrally located deflection coil unit is the same with that in said main coils.

9. A deflection yoke according to claim 5, wherein the direction of current flow in the auxiliary coil portions wound on the central winding portions of the main coils in the deflection coil unit located on each side of the centrally located deflection coil unit is the

same with that in said main coils.

10. A deflection yoke according to claim 3, wherein the plurality of deflection coil units are held together by a C-shaped retaining member, and wherein a projection formed on each side of said retaining member is fit in the associated slit in a housing accommodating said deflection coil units.

11. A deflection yoke according to claim 1, wherein n represents a winding density at a given angle β of the winding distribution of the deflection coil unit within a plane perpendicular to the tube axis, said n being given by $n = n_0 \cos^m \beta$, where n_0 represents a winding density when said angle β is zero, wherein the deflection coil unit of $m < 1$ is centrally located, and wherein the deflection coil unit of $m > 1$ is located on each side of said centrally located deflection coil unit.

12. A deflection yoke according to claim 2, wherein n represents a winding density at a given angle β of the winding distribution of the deflection coil unit within a plane perpendicular to the tube axis, said n being given by $n = n_0 \cos^m \beta$, where n_0 represents a winding density when said angle β is zero, wherein the deflection coil unit of $m < 1$ is located on the electron gun side, and wherein the deflection coil unit of $m > 1$ is located on the screen side.

13. A deflection yoke according to claim 1, wherein each of the two deflection coils having a pincushion magnetic field distribution comprises a plurality of coils arranged contiguously with a distance therebetween in the direction of the tube axis, and wherein said distance between said deflection coils is adjustable.

14. A deflection yoke according to claim 13, wherein a metal joint is secured at one end thereof to one of the deflection coils and is formed with a slit at the other end thereof, and wherein the other of the deflection coil units is movably mounted in said slit, whereby the distance between said deflection coil units is adjustable.
